TIRE

Jean Bernard Montagne, Cebazat, France, assignor to
Compagnie Generale des Etablissements Michelin,
raison sociale Michelin & Cie, Clermont-Ferrand,
France

Filed Jan. 22, 1973, Ser. No. 325,758

Term of patent 14 years

Int. Cl. D12—15
U.S. Cl. D12—146

FIG. 1

FIG. 2

FIG. 3

FIG. 4

FIG. 1 is a perspective view of a tire showing my new design, it being understood that the tread design is repeated throughout the circumference of the tire, the opposite side being substantially the same as that shown;

FIG. 2 is a fragmentary plan view thereof;

FIG. 3 is an enlarged fragmentary plan view thereof; and

FIG. 4 is an enlarged fragmentary sectional view thereof.

I claim:

The ornamental design for a tire, as shown.
